(57) **CLAIM**

The ornamental design for a femur stem with medially recessed porous coating, as shown and described.

DESCRIPTION

FIG. 1 is a perspective view showing the front, top and left sides of the femur stem with medially recessed porous coating;

FIG. 2 is a left side elevation view of the femur stem with medially recessed porous coating, the right side elevation view being a mirror image thereof;

FIG. 3 is a rear elevation view of the femur stem with medially recessed porous coating;

FIG. 4 is a front elevation view of the femur stem with medially recessed porous coating;

FIG. 5 is a top plan view of the femur stem with medially recessed porous coating; and,

FIG. 6 is a bottom plan view of the femur stem with medially recessed porous coating.

The dotted line depictions in the drawings are for illustrative purposes only, and do not form a part of the claimed design.
